UNITED STATES PATENT OFFICE.

ROSS J. HOFFMAN, OF BINGHAMTON, NEW YORK.

DAMPER-REGULATOR.

SPECIFICATION forming part of Letters Patent No. 392,514, dated November 6, 1888.

Application filed May 1, 1888. Serial No. 272,449. (No model.)

To all whom it may concern:

Be it known that I, ROSS J. HOFFMAN, of 5
Binghamton, in the county of Broome and
State of New York, have invented a new and
useful Improvement in Damper-Regulators;
and I do hereby declare that the following is a
full, clear, and exact description of the same.

My invention is an improvement in damper- 10
regulators for controlling the fire under steam-
boilers of that class which are actuated by the
steam operated through a regulating-valve
upon a piston working in the cylinder and
connected to the damper.

The invention consists, first, in the combi- 15
nation, with a piston and a steam-passage com-
municating with the cylinder at one end to
raise the piston, of a regulator-valve in said pas-
sage and an open steam-passage communicat-
ing with the other end of the cylinder, whereby 20
the piston is moved in both directions through
the agency of the steam to open or close the
damper.

My invention further consists in interposing 25
a yielding connection between the piston and
the steam-controlling valve, whereby the move-
ment of the piston under the excessive pres-
sure of the steam may aid in returning the
valve to its seat to cut off the steam from the 30
cylinder.

30 In the accompanying drawings, Figure 1 repre-
sents my improved apparatus with the valves
and pipes in central vertical section, and Fig.
2 shows the invention applied to a steam-
boiler.

35 In the drawings, A represents a cylinder, in
which works a piston, B, the outer end of which
is connected to the damper C in the ordinary
manner, so that when the piston is forced out-
ward the damper is closed and when the piston 40
returns the damper is opened. The piston
works through a stuffing-box, as shown; but
any convenient means for closing the end of
the cylinder may be used. The casting D forms
an intermediate connection between the cyl- 45
inder and the boiler or support thereof to
which the apparatus is attached. In a recess
in this is located the pressure-valve E, which
when on its seat closes the opening between
the steam-passages c' c'. I have shown a spring, 50
F, for applying the pressure to this valve, as
the more convenient means; but a weight may

be used as the well-known equivalent of the
spring for this purpose. The plug G serves to
adjust the tension of the spring to the amount of
steam-pressure required. The stem of the valve 55
extends through the plug and is connected to
the piston at its outer end to cause the piston
in moving outward to aid in closing the valve.
This connection, as shown in my patent, No.
347,799, granted August 24, 1886, is rigid and 60
positive, so that after the piston begins to op-
erate upon the connection it acts positively on
the valve. In order to modify this positive
action, I interpose a spring between the valve
and the piston, so that the first part of the 65
movement of the piston is taken up by the
spring and the force of the moving piston is
exerted on the valve gradually as the tension
of the spring increases. The precise form of
connection shown is not material, but is sim- 70
ple and effective. It consists of a bell-crank
lever, y, pivoted on an arm on the casting, one
end of the lever being connected to the valve-
stem and the other to a rod, H, extending
alongside of the cylinder. A spring, K, coiled 75
around the rod and connected therewith at the
lower end, is also connected at its upper end
with the outer end of the piston by means of
an arm, L. When the piston rises or is forced
out, its movement extends the spring, and 80
thus draws upon the rod and tends to aid the
spring in pressing the valve to its seat with a
gradual pressure, and thus gradually moves
the damper in closing as the steam rises.
It thus is fitted to gradually meet the rising 85
steam and control the fire until the amount of
fire is adapted to the required amount of steam,
whereas in the regulator shown in my said
patent the tendency of the piston movement
was to close the valve suddenly, and not to 90
open it until the steam had considerably fallen,
thus causing a more uneven action. In order
to limit the movement of the piston after it has
done its work, and to prevent any more steam
from entering the cylinder thereafter, which 95
would be useless and tend to cause leaking
around the piston, I place an adjustable stop,
h, on the rod, with a buffer-spring, l, between
it to prevent injury to the connections.

To cause the prompt release of the piston 100
after it has acted in closing or partially clos-
ing the damper to a proper extent, I provide

a steam-passage to the upper end of the cylinder. In the form shown this passage consists of a pipe, M, constantly open, so that some steam-pressure is always on the upper 5 side of the piston; and to lessen this, in order that the steam on the other side may move it, I reduce the surface on the upper side by enlarging the stem, so that the surface is (for example) about one-half that of the lower side. 10 The difference in pressure is sufficient to move the piston. A drip-cock, m, is placed in the chamber in which the valve is located, which may be left open sufficiently to allow the escape of the water of condensation and any 15 steam that may be inclosed when the valve is on its seat. The lower end of the pipe M is joined to a union which may hold the casting to the stem on the boiler; but these are immaterial details, which may be left to the skill of 20 the workman.

I have described the yielding connection between the piston and the pressure-valve to consist of a spring. This is the simplest and best; but of course a weight is well known as 25 an equivalent for a spring, and may be used instead of the spring.

The damper is shown at *c* and is in connection to the piston by rods *a b*.

I do not claim, broadly, enough to include 30 a jointed connecting-rod between a piston and valve.

I claim as my invention—
 1. In combination with the piston and steam-pressure valve of a damper-regulator, a yielding connection continuous between said piston and valve, whereby the action of the piston on the valve is made gradual, substantially as described. 35

2. In combination with the piston and steam-pressure valve of a damper-regulator, a spring-connection continuous between the piston and the steam-pressure valve, whereby the action of the piston in closing the valve is made gradual, substantially as described. 40

3. In combination with the piston and a steam-pressure valve in a damper-regulator, a bell-crank lever, a rod connected thereto, and a spring connected to the piston, with an adjustable buffer-stop on the rod, substantially as described. 45

4. In combination with the piston, a steam-valve, a yielding connection between the two, said valve being arranged in a steam-passage leading to the cylinder at the bottom of the piston, and a steam-passage leading from the 55 inlet to the upper side of the piston for returning it, substantially as described.

5. In combination with the piston and steam-pressure valve of a damper-regulator, a yielding connection continuous between said piston and valve, said piston having unequal steam-surfaces, a steam-passage controlled by said valve leading directly to the lower and larger face of the piston, and a second steam-passage leading to the opposite and smaller face of the 65 piston, said second passage being always open, substantially as described. 60

In testimony whereof I have signed my name to this specification in the presence of two subscribing witnesses.

ROSS J. HOFFMAN.
